UNITED STATES PATENT OFFICE

JOHN HENRY SUTTER, OF ARLINGTON HEIGHTS, ILLINOIS, ASSIGNOR TO BENJAMIN ELECTRIC MFG. COMPANY, OF DES PLAINES, ILLINOIS, A CORPORATION OF ILLINOIS

DESIGN FOR A PORTABLE LIGHTING FIXTURE

Application filed November 27, 1931. Serial No. 41,863. Term of patent 3½ years.

To all whom it may concern:

Be it known that I, JOHN HENRY SUTTER, a citizen of the United States, residing at Arlington Heights, in the county of Cook and State of Illinois, have invented a new, original, and ornamental Design for a Portable Lighting Fixture, of which the following is a specification, reference being had to the accompanying drawing, forming a part thereof.

The figure is a perspective view of a portable lighting fixture embodying my invention.

I claim:

The ornamental design for a portable lighting fixture substantially as shown.

JOHN HENRY SUTTER.
